ELECTRONICALLY CONTROLLED
KNITTING MACHINE

Walter Larkin, Norristown, Pa., assignor, by
mesne assignments, to Fidelity Machine Com-
pany, Inc., Philadelphia, Pa., a corporation of
Pennsylvania

Application October 3, 1945, Serial No. 620,114

12 Claims. (Cl. 66—56)

1

This invention relates to variable speed drives for knitting machines, and particularly to drives for circular knitting machines adapted for knitting seamless hosiery in tubular strip form, wherein each stocking unit includes a welt section, a leg section, a heel pocket, a foot section, a toe pocket and in most cases a separation or ravel section between units.

During the knitting of these different parts of each stocking unit it is frequently necessary to change yarns or to add reinforcing yarns. During such changes of yarns, or the feeding or reinforcing yarns, and during the reciprocating action of the needle cylinder or the cam ring associated therewith, and the corresponding reciprocating action of the sinker ring while knitting the heel and toe pockets, it has been found to be desirable to vary the knitting speed in relation to the normal knitting speed employed in the circular knitting of the leg and foot portions of the stocking unit.

Also in knitting stocking strips from different base yarns, such as natural thread silk, artificial silk, mercerized cotton, rayon, nylon or other synthetic filament yarns, it has been found advisable to establish a predetermined base speed for each of these types or qualities of yarn and to vary the speeds for knitting the different parts of each stocking unit from the established base speed in order to produce the highest quality fabric at the greatest possible speed.

These various speeds during the knitting of the different parts of a stocking unit have been deemed necessary to prevent damage to the needles, sinkers and other related parts of the machine and to the fabric in order to prevent stoppages resulting from broken or bent needles, etc., and in order to give a uniform stitch and a consequent uniform fabric free of needle or sinker marks.

The change speed mechanism of a circular knitting machine normally affords a high speed for continuous circular knitting and a slow speed for reciprocating knitting, but no variation in speed for yarn changing, yarn reinforcing, or for knitting different kinds and/or weights of yarn.

The principal object of the present invention is to provide a very sensitive and readily variable speed mechanism to an ordinary circular hosiery knitting machine, whereby the knitting speed of the machine may be quickly and automatically changed and varied to any desired extent with respect to the base speed established for knitting of the particular kind or weight of yarn of which the major portion of the stocking strip is to be formed.

For the purposes of the present invention the type of change speed mechanism best suited for putting into effect the objects of the present in-

2

vention is what is popularly termed the "electronic motor control" such as disclosed in the following patents of the General Electric Company, through which such units are commercially available, i. e. 5 U. S. Patents No. 1,654,949, No. 1,654,989, No. 1,655,036, No. 1,655,040, No. 1,719,866, No. 1,847,-934, No. 1,851,692, No. 1,904,483.

In the present case no claim is made to this so-called "electronic control" unit per se but only 10 as to its application to a circular knitting machine broadly and more specifically to a circular knitting machine equipped with an ordinary pattern drum by which the shifting from the continuous circular knitting to reciprocating knitting and vice versa are controlled and by which a plurality of yarn fingers are selectively moved into and out yarn feeding relation to the needles and sinkers of the machine for effecting yarn changes and reinforcements etc.

These "electronic control" units are in themselves controlled, in the commercial adaptations thereof, by a rotary type potentiometer, and in the present instance the potentiometer is controlled by the pattern drum of the knitting machine, whereby, as the pattern drum is intermittently rotated step by step a speed-control cam thereof will control the position of the rotor element of the potentiometer with respect to the stator element thereof to vary the speed of the knitting machine in accordance with the current operation of the machine as directed by the pattern drum.

In the accompanying drawings:

Fig. 1 is a more or less diagrammatic side elevation, partly in section, of sufficient of a conventional type of circular hosiery knitting machine to illustrate the present invention, and as would be viewed along the line 1—1, Fig. 2;

Fig. 2 is a vertical sectional elevation as taken 40 on the line 2—2, Fig. 1;

Fig. 3 is a diagrammatic planar development of the peripheral surface of the pattern drum shown in Figs. 1 and 2;

Figs. 4 and 5 illustrate a detail of the invention 45 and show the means for establishing a base speed for the knitting machine for one predetermined kind of knitting yarn;

Fig. 6 is a diagrammatic view showing the motor circuit control unit as being operated directly from the pattern chain of the machine, and

Fig. 7 is an elementary circuit diagram for controlling the speed of the driving motor of the knitting machine.

As shown in the drawings the cam ring 2 of the 55 knitting machine, in the present instance, is held stationary and is rigidly secured to the top frame 1 of the knitting machine. The knitting or needle cylinder 3 is of the rotary type and is adapted to rotate about a vertical axis within the cam

ring 2. The sinker ring mechanism is illustrated generally at 4.

The needle cylinder 3 is provided with an integral bevel gear 5 which meshes with and is rotated by a bevel gear 6, which latter is fixedly mounted for rotation on a horizontal shaft 7. The shaft 7 is rotatably mounted in suitable bearings in opposite side frame members 8 and 9 of the machine.

Loosely mounted for rotation about the axis of the shaft 7, at opposite ends respectively of the hub 10 of the bevel gear 6, are spur gears 11 and 12 respectively. The spur gear 11 meshes with a spur gear 13 which is rotatably mounted on a fixed stud shaft 14 carried by the side frame member 8. The gear 13 meshes with a pinion 15 which is fixed to a jack shaft 16 having one end rotatably supported in the frame member 8 and its opposite end rotatably supported in a bracket 17 carried by the base frame 18 of the machine.

Secured to the jack shaft 16 is a second spur gear 19 which meshes with a spur gear 20. The spur gear 20 is secured to a take-off shaft 21 which is rotatably mounted in the bracket 17 and a corresponding bracket 17a on the base frame 18.

Secured to the take-off shaft 21 is a bevel gear 22 which meshes with a bevel pinion 23, which latter is secured to the rotor shaft 24 of an electric driving motor 25, said motor being rigidly fixed in and to the base frame 18 of the knitting machine.

The spur gear 13, referred to above, is provided with a crank pin 26 on which is rotatably mounted one end boss or hub 27 of a pitman 28, the opposite end hub 29 of which is rotatable on a pin 30 secured in one arm 31 of a gear segment lever 32. The lever 32 is secured to one end of a shaft 33 which is mounted for oscillation in the framework of the machine. The lever 32 includes a gear segment 34 which is constantly in mesh with the spur gear 11 at one end of the hub 10 of the bevel gear 6 which drives the cylinder 3 through the bevel gear 5.

The hub 10 of the gear 6 is splined axially at 35 for reception and operation of a sliding clutch key 36. The key 36 is carried by a sleeve 37 which is slidably mounted on the outside of the hub 10 and is provided with an annular circumferential groove 38 for reception of a clutch yoke 39.

The clutch yoke 39 is pivotally carried in the outer end of a clutch shifting lever 40 which latter is pivotally mounted on a pin 41 in a boss 42 on the under side of the top frame 1 of the machine.

The clutch key 36 is shiftable longitudinally in the spline 35 of the gear hub 10, into end grooves 43 and 44 in the gears 11 and 12 respectively, so that the hub 10 may be rigidly coupled to the gear 11 for oscillating the needle cylinder 3 or to the gear 12 for rotating the cylinder 3.

The shifting of the clutch key 36 is effected by cam plates 45, 46, 47 and 48 secured to the peripheral surface 49 of the pattern drum 50.

The pattern drum 50 is secured to a shaft 51 which is rotatably mounted in the framework of the knitting machine. Secured to the shaft 51 is a ratchet wheel 52 which is engageable by a pawl 53 for advancing the pattern drum 50 step by step.

The pawl 53 is pivotally mounted on a lever 54 which is secured to the shaft 33. This shaft 33 is continuously oscillated through the arm 31 and

pitman 28 from the crank pin 26 on the continuously rotating gear 13.

The pawl 53 is held out of mesh with the ratchet wheel 52, at predetermined intervals by a kick-out arm or latch 55 which is pivotally mounted on the frame and operates against a pin 56 which projects laterally from the pawl 53. The latch 55 in turn is controlled by high links of a pattern chain (not shown) which rides on a chain wheel 57 engaging one arm 58 of the latch 55.

The chain wheel 57 is freely rotatably mounted on the pattern drum shaft 51 and is advanced step by step by a ratchet wheel 59 which is secured to the chain wheel 57 for rotation therewith. The ratchet wheel 59 is advanced step by step by a pawl 60 pivotally mounted on the pawl lever 54 secured to the constantly oscillating shaft 33.

On the peripheral face 49 of the pattern drum 50 is a plurality of segmental circumferentially arranged and laterally spaced cam piece series 61, 61, which control the operation of a plurality of yarn change fingers 62, 62 etc. through lift levers 63, 63 respectively. These lift levers 63, 63 are pivotally mounted on a cross shaft 64, which is non-rotatably mounted in the framework of the knitting machine.

Pivotedly mounted on the shaft 64 is a lever 65 on which is rotatably mounted a cam follower roller 66. This cam follower 66 is adapted to ride high, low and intermediate lifts 67a, 67b, 67c, of a ring cam 67 secured to one end of the pattern drum 50. There may be as many of these lifts as there are speed variations required of the driving motor 25 during the knitting of a complete repeat in the string of stocking units knitted by the needles (not shown) operating in the needle grooves of the cylinder 3 by the cams (not shown) in the cam ring 2.

The speed variations of the driving motor 25 are controlled by the electronic unit referred to above as being disclosed in one or more of the prior U. S. patents listed above.

The electronic control unit in turn is controlled by a potentiometer 70, see Figs. 4 and 5, which includes an outer casing 71 which for the purposes of this disclosure will be termed the stator, and an internal element secured to a shaft 72 which will be hereinafter referred to as the rotor.

The specific construction of the potentiometer 70 need not be shown or described in detail as it is of a conventional type well known as to construction and mode of operation by anyone having the most elementary knowledge of electricity.

For the purpose of this invention, the stator 71 is axially aligned and concentric with the rotor shaft 72 of the potentiometer 70 and the shaft 72 is rotatably mounted in a bearing 73 mounted in a bore 74 formed in the side frame 8 of the knitting machine.

In order to retain the stator in a fixed predetermined position for setting the potentiometer for maintaining the speed of the motor 25, through the electronic unit disclosed in the aforesaid prior U. S. patents, at a predetermined number of revolutions per minute, as a base speed for any given knitting yarn, the stator is secured to an arm 75 having a spring pressed detent 76 at its outer end for entering one of a plurality of openings 77, 77 formed in the side frame 8, so that the stator 71 may be bodily turned about the axis of the rotor shaft 72 to any one of the angular positions determined by the location of the keeper holes 77.

The rotor, as is common in potentiometers, is adapted to be turned within the stator to increase or decrease the voltage of the line of the electric circuit in which the potentiometer is installed, depending upon the direction in which the rotor is turned, and in order to effect such turning of the rotor within the stator 71 the rotor shaft 72 is provided with a spur pinion 78 which meshes with a gear segment 79, which latter is rigidly secured to the lever 65. The lever 65 as previously noted carries the cam follower 66 and this cam follower is maintained in constant contact with the speed control cam 67 by a spring 80.

From the foregoing description, it will be clear that once a base speed for the motor 25 is established for a given knitting yarn, by inserting the spring pressed detent 76 in one of the keeper holes 77, greater or lesser speeds of the motor 25 may be attained by turning the rotor shaft 72 of the potentiometer with respect to the stator, i. e. turning the shaft 72 in one direction will effect an increase in the speed of the motor 25 and turning the shaft 72 in the opposite direction will effect a decrease in the speed of the motor 25.

It will also be clear that the speed changes of the motor 25 are coordinated with the various mechanical changes etc. in the operation of the knitting machine as determined by the step by step movements of the pattern drum 50, by reason of the fact that the high, low and intermediate lobes of the speed change cam 67 bear definite fixed relation to the cam segments 45 to 48 and 61, 61 on the pattern drum 50 by which such mechanical changes in the operation of the knitting machine are controlled.

It will also be clear that by varying the relative heights of the lobes on the speed change cam 67 and distributing them discriminately around the circumference of the pattern drum 50 an infinite number of relatively different speeds, within a given bracket, may be caused to be effected by the motor 25; and that by changing the position of the stator about the axis of the rotor shaft these speed brackets may be changed in accordance with the different knitting yarns employed, or for other reasons if desired.

As shown in Fig. 6, the potentiometer 70 may be controlled directly from the pattern chain of the machine, which in this instance is designated by the reference character 81 and which lays around the upper half of the sprocket 57. The chain 81 comprises a series of links of various heights 81a, 81b, 81c, etc. corresponding, for example, with the relative elevations of the lobes 67a, 67b, 67c, etc. of the ring cam 58 shown in Fig. 1.

The potentiometer 70, as hereinbefore described, is actuated by a pinion 78 on the rotor shaft 72 thereof, and this pinion 78 meshes with a gear segment 79 loosely mounted on the shaft 64. In the present instance, Fig. 6, the gear segment 79a is secured to one end of a cross shaft 64a and the cam follower arm 65 of Fig. 1 is replaced by an arm 65a secured to the distant end of the shaft 64a. This arm 65a has its outer end shaped to ride the high, low and intermediate links 81a, 81b, 81c of the pattern chain 81 to rock the shaft 64a to varying degrees for correspondingly oscillating the rotor of the potentiometer.

Fig. 7 shows the electronic circuit for controlling the speed of the motor 25, through the adjustment of the potentiometer 70. The motor armature is represented at 90, while the motor field is represented at 91. The field current is

supplied from a transformer 92 by means of a full wave rectifier 93, while the armature is supplied with current from the transformer 92 through a pair of controlled rectifiers 94 and 95. 5 As indicated, the tubes 93, 94, and 95 are gas-filled tubes. The potentiometer 70 serves in conjunction with a tube 96 and a potentiometer 97 to control the operation of tubes 94 and 95 through the grid circuits thereof designated generally by reference character 98. The details of operation are unimportant here, since the electronic control circuit is old per se and the present invention is concerned only with the operation of the potentiometer 70 by the pattern mechanism 15 of the knitting machine.

I claim:

1. A circular knitting machine comprising an individual electric driving motor, pattern mechanism for governing predetermined operations 20 of said machine, an electronic speed control circuit for and including said motor, a variable control unit for said circuit, and means coordinated with said pattern mechanism for operating said variable control unit for varying the speed of said motor in accordance with changes 25 in the operations of said machine as prescribed by said pattern mechanism.

2. A circular knitting machine comprising a pattern drum for governing predetermined operations of said machine, an individual electric driving motor for said machine, an electronic speed control circuit for and including said motor, a variable control unit for and forming part of said circuit, said variable unit comprising a normally fixed element and a relatively rotatable element, means for turning said rotatable element relative to said fixed element including a cam follower, and a cam comprising a plurality of lobes of different heights carried by 35 said pattern drum and engageable with said cam follower for actuating said unit to effect variations in the speed of said motor in accordance with variations in the operations of said machine as prescribed by said pattern drum.

3. A circular knitting machine comprising a pattern drum for governing predetermined operations of said machine, an individual electric driving motor for said machine, an electronic speed control circuit for and including said motor, a variable control unit for and forming part of said circuit, said variable unit comprising a normally fixed element and a relatively rotatable element, means for turning said rotatable element relative to said fixed element including a cam follower, a cam comprising a plurality of lobes of different heights carried by said pattern drum and engageable with said cam follower for actuating said unit to effect variations in the speed of said motor within a predetermined range 50 in accordance with variations in the operations of said machine as prescribed by said pattern drum, and manually operable means for varying the position of said normally fixed element about the axis of rotation of said rotatable element for varying said range as a whole from one bracket of speed variations of said motor to another such bracket.

4. A circular knitting machine comprising an individual electric driving motor adapted to rotate in one predetermined direction, a pattern drum for governing predetermined operations of said machine, an electronic speed control circuit for controlling the speed of said motor in said direction solely, and means carried by said pattern drum for controlling said circuit to change 70 75

the speed of said motor in said direction solely in accordance with changes in the operations of said machine as prescribed by said pattern drum.

5. A circular knitting machine comprising an individual electric driving motor, a pattern drum for governing predetermined operations of said machine, a variable unit for controlling the speed of said motor, said unit comprising a normally fixed element and a relatively rotatable element, a lever for rotating said rotatable element, and a cam carried by said pattern drum for rocking said lever and thereby actuating said unit to change the speed of said motor in accordance with changes in the operations of said machine as prescribed by said pattern drum.

6. A circular knitting machine comprising an individual electric driving motor, a pattern drum for governing predetermined operations of said machine, a variable unit for controlling the speed of said motor, said unit comprising a normally fixed element and a relatively rotatable element, a lever for rotating said rotatable element, a cam carried by said pattern drum for rocking said lever and thereby actuating said unit to change the speed of said motor in accordance with changes in the operations of said machine as prescribed by said pattern drum, and manually operable means for rotating said normally fixed element to vary the range of speed changes of said motor.

7. A circular knitting machine comprising a pattern drum for governing predetermined operations of said machine, an individual electric motor for driving said machine, a potentiometer for varying the speed of said motor, and means on said pattern drum for actuating said potentiometer to change the speed of said motor in accordance with operational changes of the machine as prescribed by said pattern drum.

8. A circular knitting machine comprising a pattern drum for governing predetermined operations of said machine, an individual electric motor for driving said machine, a potentiometer for varying the speed of said motor and comprising a rotor shaft, a pinion on said shaft, a gear segment meshing with said pinion, a lever concentric with and integrally connected to said gear segment for concurrent pivotal movement about a fixed axis, a cam follower on said lever, and a ring cam secured to said pattern drum and including a plurality of lobes of different heights spaced circumferentially around said drum for successively contacting said cam follower to actuate said potentiometer for varying the speed of said motor in accordance with operational changes of said machine as prescribed by said pattern drum.

9. A circular knitting machine comprising a pattern drum for governing predetermined operations of said machine, an individual electric motor for driving said machine, a potentiometer for varying the speed of said motor and comprising a rotor shaft, a normally fixed stator encircling said rotor shaft, a pinion on said shaft, a gear segment meshing with said pinion, a lever concentric with and integrally connected to said gear segment for concurrent pivotal movement about a fixed axis, a cam follower on said lever, a ring cam secured to said pattern drum and including a plurality of lobes of different heights spaced circumferentially around said drum for successively contacting said cam follower to actuate said potentiometer for varying the speed of said motor in accordance with operational changes of said machine as prescribed by said

pattern drum, an operating arm on said stator, and a manually operable detent on the outer end of said arm adapted to be selectively entered into a plurality of fixed relatively spaced keeper holes formed in said machine for varying the speed ranges of said motor within predetermined brackets respectively in accordance with the keeper hole entered by said detent.

10. A circular knitting machine comprising a pattern drum for governing predetermined operations of said machine, an individual electric motor for driving said machine, a potentiometer for varying the speed of said motor and comprising a rotor shaft, a normally fixed stator encircling said rotor shaft, a pinion on said shaft, a gear segment meshing with said pinion, a lever concentric with and integrally connected to said gear segment for concurrent pivotal movement about a fixed axis, a cam follower on said lever, a ring cam secured to said pattern drum and including a plurality of lobes of different heights spaced circumferentially around said drum for successively contacting said cam follower to actuate said potentiometer for varying the speed of said motor in accordance with operational changes of said machine as prescribed by said pattern drum, an operating arm on said stator, a manually operable detent on the outer end of said arm adapted to be selectively entered into a plurality of fixed relatively spaced keeper holes formed in said machine for varying the speed ranges of said motor within predetermined brackets respectively in accordance with the keeper hole entered by said detent, and an electronic motor control circuit including said driving motor and said potentiometer for governing the speed of said motor in accordance with the circumferential relationship of said rotor shaft and said stator as prescribed by said detent and said ring cam.

11. A circular knitting machine comprising an individual electric driving motor therefor adapted to rotate in one predetermined direction, pattern mechanism for governing predetermined operations of said machine, an electronic speed control circuit for varying the speed of said motor in said direction solely, and means carried by said pattern mechanism for controlling said circuit.

12. A circular knitting machine comprising an individual electric driving motor therefor adapted to rotate in one predetermined direction, pattern mechanism including a link chain for governing predetermined operations of said machine, an electronic speed control circuit for controlling the speed of said motor in said direction solely, and a series of links of different heights included in said pattern chain for controlling said circuit to vary the speed of said motor in said direction solely.
